UNITED STATES PATENT OFFICE.

JOHN ARTHUR KAYE, OF SAULT STE. MARIE, ONTARIO, CANADA.

MINING-DRILL.

1,277,220.

Specification of Letters Patent. Patented Aug. 27, 1918.

Application filed June 15, 1918. Serial No. 240,152.

To all whom it may concern:

Be it known that I, JOHN ARTHUR KAYE, a subject of the King of Great Britain, residing at Sault Ste. Marie, Province of Ontario, in the Dominion of Canada, have invented a new and useful Mining-Drill; and I do hereby declare the following to be a full, clear, and exact description of the invention, such as will enable others skilled 10 in the art to which it appertains to make and use the same.

The present invention relates to a mining drill, and has for its object to provide a device of this character which embodies novel 15 features of construction whereby a reciprocating drill of either a large or a small size can be effectively operated by a single man.

Further objects of the invention are to provide a mining drill which is portable and 20 can be easily carried from place to place, which provides a manually operated mechanical means for reciprocating and turning the drill bit in the proper manner, and which can be easily mounted in operative 25 position.

With these and other objects in view, the invention consists in certain novel combinations and arrangements of the parts as will 30 more fully appear as the description proceeds, the novel features thereof being pointed out in the appended claims.

For a full understanding of the invention, reference is to be had to the following description and accompanying drawing, in 35 which:—

Figure 1 is a vertical sectional view through a mining drill constructed in accordance with the invention.

Fig. 2 is a side elevation thereof.

Fig. 3 is a detail view of the hammer operating mechanism at the upper end of the drill rod.

Fig. 4 is an enlarged detail view of one of the adjustable stop members which are applied to the wires.

Fig. 5 is a bottom plan view of the reciprocating weight, showing the ring to which the upper ends of the wires are attached.

Corresponding and like parts are referred 50 to in the following description and indicated in all the views of the drawings by the same reference characters.

Referring to the drawings, the numeral 1 designates a base which has a hollow formation 55 and is substantially frusto-conical in shape, the lower edge of the base being pro-

vided with teeth 2 which are adapted to bite into the surface of the rock or other formation to which the device is applied and hold the drill firmly in position. A sleeve 3 extends into the base from the top thereof and is rigidly connected to the base, said sleeve being open at both ends and receiving the lower end of a tubular guide 4 which is adjustable therein and projects upwardly above the base. This tubular guide 4 is both removable and adjustable, and loosely receives a reciprocating stock 5 which is provided at its lower end with a conventional drill bit 6. In the present instance the 70 tubular guide 4 is shown as threaded in the sleeve 3, a jam nut 7 being provided to hold the parts in an adjusted position.

The reciprocating bit 5 has a diameter considerably smaller than the interior diameter of the tubular guide 4, and a cross head 8 is secured to the upper end thereof, said cross head being provided with a pair of standards 9 which project upwardly therefrom and extend above the tubular guide 4. 75 A short horizontal shaft 10 is journaled between the upper ends of the standards 9 and has a pulley or drum 11 rigidly fitted upon the middle portion thereof. The ends of the shaft are rigidly connected to the bifurcated 80 end of an operating lever 12 which provides a means for rotating the shaft to wind a cable 13 on the drum 11, and also for turning the stock 5 step by step about a vertical axis to shift the position of the drill 85 bit 6 in the necessary manner. The cable 13 is connected at its lower end to an eye 14 which projects from the top of a weight 15 and has a swivel connection therewith, said weight being adapted to be lifted by the 90 winding of the cable 13 on the drum 11, and to drop with a hammer-like action on the upper end of the stock 5 when released.

A series of wires 16 are pendent from the periphery of the weight 15 and pass loosely 100 through openings 17 in a disk 18 which is rigidly applied to the stock 5 at a point spaced from the upper end thereof, and which is loose within the tubular guide member 4. The upper ends of the wires 16 are anchored in a ring 19 which is let into the edge portion of the weight at the bottom thereof, being removably held in position by suitable fastening members such as the screws 20. The lower ends of the 105 wires 16 are each provided with a weight 21 which serves as a stop to engage the disk 18.

2
when the hammer 15 has reached the upper limit of its movement, and also to hold the wire taut on the downward movement of the hammer so that the wire will slide freely 5 through the opening 17 of the disk instead of bending outwardly into the path of the hammer.

In the operation of the mining drill the operating lever 12 is manipulated to rotate 10 the drum 11 and wind the cable 18 thereon, thereby raising the hammer 15 until the weights 21 at the lower ends of the wires 16 engage the disk 18. The operating lever is then released, whereupon the hammer 15 descends 15 and strikes a sharp blow upon the upper end of the stock 5. This blow is transmitted through the stock to the drill bit 6, and by repeating this operation successive blows are delivered upon the stock in the necessary manner 20 to drive the drill bit into the rock or other formation being worked upon. At short intervals of time the stock and drill bit are rotated step by step about a vertical axis by swinging the operating lever 12 laterally. 25 thereby shifting the position of the cutting edge of the drill bit at proper intervals of time. As the hole which is drilled becomes deeper, drill rod sections 22 may be successively added, so that a drilling string of the 30 necessary length for operating at any ordinary depth can be provided. It will be obvious that by removing the tubular guide 4 the stock 5 and drilling string can be lifted from the opening, thereby enabling the 35 drill bit to be sharpened or replaced, or an additional section 22 to be added to the drilling string. For the purpose of enabling water to be supplied to the drill opening, the base 1 is provided with a water pipe 24 40 which is inclined downwardly from one of the sides thereof and opens through the interior of the sleeve 3. Water which is poured into the pipe 24 will be directed into the orifice so that it will descend to the bottom 45 of the hole and supply the necessary moisture for the proper and effective operation of the drill bit. The weights 21 at the lower ends of the wires 16 are adjustably applied to the wires so that they can be 50 positioned to regulate the stroke of the hammer 15. For this purpose the weights may be slidable on the wires and provided with tapered and bifurcated ends 21^a which are threaded to receive clamping nuts 25. When 55 these nuts 25 are tightened the jaws provided by the bifurcated end of the weight are caused to securely grip the wire to hold the weight in an adjusted position. It will thus be obvious that by properly positioning the weights the device can be adjusted 60 for a long or a short hammer stroke, depending upon the character of the formation being operated upon, as well as upon the size and character of drill bit being used.

65 Having thus described the invention, what

I claim as new and desire to secure by Letters Patent, is:—

1. A mining drill including a tubular guide, a stock mounted to reciprocate within the guide, a drill bit carried by the lower 70 end of the stock, a cross head applied to the upper end of the stock, a frame projecting upwardly from the cross head, a reciprocating weight mounted above the cross head, and means upon the frame for lifting and 75 dropping the weight.

2. A mining drill including a tubular guide, a stock mounted to reciprocate within the guide, a drill bit carried by the lower 80 end of the stock, a cross head applied to the upper end of the stock, a frame projecting upwardly from the cross head, a drum journaled within the frame, a cable connected to the drum, a reciprocating weight mounted above the cross head and connected to the 85 cable, and means for operating the drum to elevate and drop the weight.

3. A mining drill including a tubular guide, a stock mounted to reciprocate within the guide, a drill bit carried by the lower 90 end of the stock, a cross head applied to the upper end of the stock, a frame projecting upwardly from the cross head, a drum journaled upon the frame, a reciprocating weight mounted above the cross head, a cable operatively connecting the weight and drum, means for operating the drum to raise and drop the weight, and stop means for limiting the movement of the weight. 95

4. A mining drill including a tubular guide, a stock mounted to reciprocate within the guide, a drill bit carried by the lower end of the stock, a cross head applied to the upper end of the stock, a frame projecting upwardly from the cross head, a reciprocating weight mounted above the cross head, means upon the frame for lifting and dropping the weight, wires pendent from the weight, and means coöoperating with the wires to limit the upward movement of the 100 weight. 105

5. A mining drill including a tubular guide, a stock mounted to reciprocate within the guide, a drill bit carried by the lower end of the stock, a cross head applied to the upper end of the stock, a frame projecting upwardly from the cross head, a reciprocating weight mounted above the cross head, means upon the frame for lifting and dropping the weight, a series of wires pendent from the weight, guide means on the stock loosely engaging the wires, and stops applied to the wires for engaging the guide means to limit the upward movement of the weight. 115 120

6. A mining drill including a tubular guide, a stock mounted to reciprocate within the guide, a drill bit carried by the lower end of the stock, a cross head applied to the upper end of the stock, a frame projecting upwardly from the cross head, a recipro- 125 130

- cating weight mounted within the cross head, means upon the frame for raising and dropping the weight, a series of wires pendent from the weight, a disk surrounding the stock and provided with openings loosely receiving the wires, and weights applied to the lower ends of the wires to hold the wires taut, said weights coöperating with the disk to limit the upward movement of the weight.
7. A mining drill including a tubular guide, a stock mounted to reciprocate within the guide, a drill bit carried by the lower end of the stock, a cross head applied to the upper end of the stock, a frame projecting upwardly from the cross head, a reciprocating weight mounted above the cross head, means upon the frame for raising and dropping the weight, a ring removably applied to the weight, a series of wires pendent from the ring, guide means upon the stock loosely engaging the wires, and stops adjustably applied to the lower ends of the wires for holding the wires taut and coöperating with the guide means to limit the upward movement of the weight.
8. A mining drill including a base formed with a sleeve, a tubular guide adjustable within the sleeve and adapted to be moved in and out therein, a stock mounted to reciprocate within the tubular guide, a drill bit carried by the lower end of the stock, a cross head applied to the upper end of the stock, a frame projecting upwardly from the cross head, a reciprocating weight mounted above the cross head, and means upon the frame for lifting and dropping the weight.

In testimony whereof I have signed my name to this specification in the presence of two subscribing witnesses.

JOHN ARTHUR KAYE.
